UNITED STATES PATENT OFFICE.

JOSEPH A. McLANE, OF MORGANTOWN, WEST VIRGINIA, ASSIGNOR TO THE
ARMORCORD RUBBER COMPANY, OF MORGANTOWN, WEST VIRGINIA, A
CORPORATION OF WEST VIRGINIA.

DESIGN FOR A TREAD OF VEHICLE-TIRES.

55,808.

Specification for Design.

Patented July 13, 1920.

Application filed January 14, 1920. Serial No. 351,488. Term of patent 14 years.

To all whom it may concern:

Be it known that I, JOSEPH A. McLANE, a citizen of the United States, residing at Morgantown, in the county of Monongalia and the State of West Virginia, have invented a new, original, and ornamental Design for Treads of Vehicle-Tires, of which the following is a specification, reference being had to the accompanying drawing, forming a part thereof.

Figure 1 is a partial plan view of the tire showing the design on the tread thereof, and

Fig. 2 is a transverse sectional view of the tire taken on line 2-2 of Fig. 1.

What I claim is:

The ornamental design for a tread of vehicle tires, as shown.

JOSEPH A. McLANE.
